CARBON HOLDING DEVICE

John E. Euth, Chicago, Ill., assignor to United Autographic Register Co., a corporation of Illinois

Application January 9, 1937, Serial No. 119,852

10 Claims. (Cl. 282—29)

This invention relates to a carbon holder for use in a typewriter provided with a cylindrical platen, and more particularly to an improved anchoring tail for automatically holding transfer slips or carbon slips during a stripping operation in which the carbons are interleaved with a succeeding set of forms.

The primary object of the invention is to provide an improved carbon holding device having means for automatically engaging the platen frictionally to hold the carbons while the stationery is free to advance.

A further object of the invention is to provide an improved carbon holding device in which the carbons and anchoring tail are of substantially the same width as the stationery.

A further object of the invention is to provide a carbon holding tail having stationery guide-means at both its front and rear edge portions. Another object of the invention is to provide rear guide-means for the stationery which may be detached from the anchoring tail after the carbons are worn out.

The invention is illustrated in a preferred embodiment in the accompanying drawings, in which—

Fig. 1 is a side elevational view, partly in section and somewhat diagrammatic, showing how the stationery and interleaved carbons are fed between a platen roll and presser rolls which are standard equipment on most machines; Fig. 2, a broken plan view showing a preferred form of the carbon holding device as used in connection with continuous stationery strips; Fig. 3, a fragmentary plan view similar to Fig. 2 but taken from the opposite side; Fig. 4, an enlarged fragmentary perspective view showing how the carbon slips are fastened to the anchoring tail; Fig. 5, a broken sectional view, taken as indicated at line 5 of Fig. 2; Fig. 6, a fragmentary view showing a modified form of rear guide-means for the anchoring tail; Fig. 7, a fragmentary plan showing another modified form of rear guide-means; Fig. 8, a fragmentary plan view showing another modified form of rear guide-means; and Fig. 9, a sectional view, taken as indicated at line 9 of Fig. 8.

In the preferred embodiment illustrated in Figs. 1-5, A designates a tail-like web which serves as an anchoring device; B, carbon slips which are secured to the tail A, by means of fastening means B'; and C, rear guide-means which may be detachably secured to the rear of the anchoring tail by means of metal clips C'.

The anchoring tail may be made of ordinary

sandpaper of a comparatively fine grade, 2/0 grade being satisfactory. As shown in Figs. 2 and 5, the front marginal edge of the paper may have a V notch, as indicated at 10, to lessen the chance of the edge catching on lines of weakening usually provided between sets of forms 11 on continuous-form stationery 12.

The carbon transfer strips B may be ordinary carbon paper of substantially the same width as continuous stationery strips 12. The slips, preferably are arranged in stepped relation, as indicated in Figs. 3-5, inclusive, and their rear edge portions folded around and permanently secured to the tail A, by means of transverse gummed paper strips B', the ends of the latter being secured to the tail A. Preferably, the end portions of the strips B' are covered with gummed tabs 13 (see Fig. 2). It may be noted that the fastenings B' hold the carbon slips B in a manner that permits the stationery strips 12 to be threaded between the same and the strips B' serve to hold the carbons in lateral alignment with the stationery.

The preferred aligning means C, for the rear of the anchoring tail, is shown in Figs. 1-3 and comprises a flat cross-bar 14 and a companion parallel cross-bar 15 which may be of double thickness to provide additional rigidity. The ends of the cross-bars are joined by integrally formed end bars 16, which preferably are disposed at right angles to the plane of the bars 14 and 15, so as to provide a lateral aligning surface. The device is secured to the rear of the tail A by doubling back the rear marginal portion 17 over the cross-bar 14 and gripping the overlap by means of U-shaped spring clips C', as shown in Fig. 2. Thus after a set of carbons have become worn, they may be discarded with the anchoring tail, but the rear aligning device may be salvaged and applied to a new assembly.

The holding device is easily installed by threading all of the strips through a slot 18 provided between the bars 14 and 15 and threading them into interleaved relation with the carbon slips. This operation is facilitated by the stepped arrangement of the rear edges of the carbons. The assembly is then introduced between a platen roll 19, which usually has a soft rubber surface 20, and presser rolls 21 so that the advanced loaded set of forms may be typed in the usual manner. At the completion of the writing operation, the forms will reach the position shown in Fig. 1 and the presser rolls 21 may be thrown out of engagement with the stationery. The operator then grasps the ends of the strips 12 and draws them upwardly at an angle 55

that will press a sufficient arc of the frictional tail against the platen to bind it against forward movement and permit the interleaved stationery to slip therearound. When the completed set of forms are clear of the carbons, they may be detached and the assembly is ready to be backed into writing position by means of the platen roll and presser mechanism, as will be readily understood.

10 In the modification shown in Fig. 6, the rear edge of the anchoring strip 22 is doubled over to form a pleat 23 which may be held by staples 24. A metal bail 25 may then have its front ends introduced into the ends of the pleat 23 by bending the central portion of the pleat 23.

15 In the modification shown in Fig. 7, a metal insert 26 is mounted in a window 27 provided in the rear of an anchoring tail 28. The metal frame thus formed serves as an aligning slot 20 for the stationery.

20 In the modification shown in Figs. 8 and 9, a flat metal bar 29 has its end portions turned upwardly and inwardly over the anchoring tail 30, as indicated at 31, and is gripped in position 25 by means of metal clips 32.

25 It may be noted that in the forms shown in Figs. 3, 7 and 8, the metal aligning means serves to hold the rear edge portion of the anchoring tail in lateral extended position. In all forms 30 except Fig. 7, practically the entire holding device is disposed within the lateral boundaries of the stationery strips.

35 While sandpaper is preferred for use as an anchoring tail, other stiff papers may be used provided with a suitable frictional face. For example, it has been found that a thin sheet of rubber may be pasted to the top face of the tail and it will operate satisfactorily.

40 The foregoing detailed description has been given for clearness of understanding only, and no unnecessary limitations should be understood therefrom, but the appended claims should be construed as broadly as permissible, in view of the prior art.

45 I claim:

1. A manifolding device, for use in a typewriter having a cylindrical platen around which continuous stationery strips may be led, comprising: a flexible tail-like web to which is attached a plurality of carbon slips interleaved with said stationery, said web having a face of frictional material adapted to engage said platen so as to restrain advance of the carbons while the stationery is stripped therethrough.

55 2. A manifolding device, for use in a typewriter having a cylindrical platen roll, comprising: a flexible tail member having a frictional face adapted to engage said platen roll and automatically restrain circumferential movement with respect to the roll while stationery is drawn there-

around; a series of carbon slips connected to front marginal portions of said tail member; and guide-means at the rear of the tail member adapted to engage stationery interleaved with the carbons and hold the same in lateral alignment. 5

3. A device as specified in claim 2, in which the guide-means comprises a metal cross-bar secured to the tail member so as to hold said member laterally extended and form a passage-way for the stationery strips. 10

4. A device as specified in claim 2, in which the guide-means comprises an elongated metallic frame removably secured to the tail member so as to hold the tail laterally extended and form 15 a guide slot for the stationery.

5. A device as specified in claim 2, in which the guide-means comprises an elongated metallic frame removably secured to the tail member so as to hold the tail laterally extended and form 20 a guide slot for the stationery, said frame having a pair of flat parallel cross-bars connected at their ends by flat end-bars disposed substantially perpendicular to the plane of the cross-bars.

6. A device as specified in claim 2, in which 25 the rear end of the tail member is doubled back on itself to form a pleat, and the guide means comprises a bail having ends adapted to be inserted in opposite ends of said pleat.

7. In a typewriter having a cylindrical platen 30 and presser rolls for feeding a plurality of long strips of stationery through writing position, a carbon holding device comprising: a tail member, of the same width as the stationery strips, having a frictional face presented towards the 35 platen and adapted to prevent circumferential movement with respect thereto when said presser rolls are released; guide-means at the rear of said tail for holding the stationery strips in lateral alignment and in juxtaposition to said tail; 40 carbon slips interleaved with the strips; and fastenings for said carbon slips for securing their rear end portions to the front lateral edge portions of the tail, said fastenings forming lateral guides for the stationery at the front of 45 said tail.

8. A device as specified in claim 7, in which the tail member is made of sandpaper.

9. A device as specified in claim 7, in which the tail member is made of sandpaper and has 50 at its front marginal edge portion a V-shaped notch to avoid catching on lines of weakening provided in the stationery strips.

10. A device as specified in claim 7, in which the fastenings for the carbons comprise transverse strips of gummed tape, around which the carbons are folded, said carbons being arranged 55 in stepped relation.
